OVERHEAD DOOR AND AFFILIATED
MECHANISM

Christ Buehner, Milwaukee, Wis., assignor to
Phenix Manufacturing Company, Inc., Milwaukee, Wis., a corporation of Wisconsin

Application March 6, 1944, Serial No. 525,319

4 Claims. (Cl. 160—201)

1

This invention relates to improvements in overhead doors and affiliated mechanisms.

The overhead door of the present invention is of the type which includes more than two superimposed and foldably connected sections and arranged relative to the tracks or guiding means in a manner so that the rollers carried by the top section of the door are on supports which may project outwardly or collapse relative to said door section, whereby, for the elevation of the door a path utilizing but a minimum of head room is required. In conventional doors of the type under consideration, due to the low elevation of the overhead portion of the guiding track for the door, the upper section of the door may usually break or fold inwardly before initiation of movement of the entire door, with the undesirable result that special means must be provided for controlling the upper section of the door and to insure proper closing and latching of the same when the entire door is closed.

With the foregoing in mind it is, therefore, a primary object of the present invention to overcome the above objections by providing a multi-section overhead door of the type mentioned in which the upper section of the door breaks or folds inwardly only upon movement of the entire door with the same being accomplished by the same single operation used to initiate movement of the entire door, together with a novel latching mechanism for both the upper panel and the entire door.

A further object of the invention is to provide, in a multi-section overhead door, a novel combination latching mechanism which simultaneously and jointly latches the upper panel of the door against inward swinging movement, and latches the entire door against vertical movement.

A further object of the invention is to provide an overhead door latching mechanism having elongated control means traversing the vertical extents of several of the foldably associated door sections, said elongated control means incorporating mechanism for automatically compensating for any foreshortening tendency therein during the movement of said door sections through an arc to overhead position.

A further object of the invention is to provide, in a multi-section overhead door, latching mechanism for the door which is easily operated from exteriorly of the door by the simple manipulation of a push button.

A further object of the invention is to provide, in a multi-section overhead door, combination

lock and latch mechanism which necessitates, on the exterior of the door, a minimum of projecting hardware, thereby economizing in the head room required for the door when it is in its overhead position.

5 A further object of the invention is to provide an overhead door and affiliated mechanism of very simple construction, which is strong and durable, which is simple and efficient in operation, which permits easy and accurate installation of the door, and which is well adapted for the purposes described.

With the above and other objects in view the invention consists of the improved overhead door and affiliated mechanism and its parts and combinations as set forth in the claims, and all equivalents thereof.

In the accompanying drawings in which the same reference characters indicate the same parts in all of the views:

20 Fig. 1 is a rear or inner elevational view of the improved overhead door in its closed position and showing affiliated mechanism therefor, portions of the supporting structure being shown in section;

25 Fig. 2 is an enlarged fragmentary detail sectional view taken on line 2—2 of Fig. 1;

30 Fig. 3 is an enlarged fragmentary elevational view of an inner portion of the upper section of the door showing the latching mechanism carried thereby;

35 Fig. 4 is a vertical sectional view taken on line 4—4 of Fig. 3;

Fig. 5 is a top view of the showing in Fig. 3 with a portion of an associated angled plate being shown in section;

40 Fig. 6 is an enlarged fragmentary elevational view of the inner portion of an intermediate section of the door showing the portion of the latching and locking mechanism carried thereby;

Fig. 7 is a vertical sectional view taken on line 7—7 of Fig. 6;

45 Fig. 8 is a fragmentary vertical sectional view similar to Fig. 7, only showing the mechanism in another position;

Fig. 9 is an enlarged fragmentary vertical sectional view of a portion of the overhead door guiding mechanism; and

50 Fig. 10 is a transverse sectional view taken on line 10—10 of Fig. 9.

Referring now more particularly to the drawings, the complete, sectional, overhead door 15 is illustrated as having four sections 16, 17, 18 and 19, but in actual practice the door may include any number of sections in excess of two.

The sections 16, 17, 18 and 19 are hinged together in superimposed relation by hinges 20. For the purpose of guiding the door to and from its overhead position there are provided adjacent each side of the door a metal track 21 of channeled formation and comprising an upright section 22, a curved section 23, and an overhead horizontal section 24.

The mechanism for guiding the door to and from its overhead position, except insofar as it is associated with the improved door latching and locking mechanism with which the present application is particularly concerned, will not be described in detail, as it forms the subject matter of a separate copending application, Serial No. 525,320 filed on even date herewith, now Patent No. 2,375,837, dated May 15, 1945. The door guiding mechanism is, however, of the type which requires a minimum of head room when the door is in its overhead position. To that end, the upright sections 22 of the tracks 21 terminate below the upper edge of the closed door so that the curved sections 23 of the tracks 21 curve upwardly and inwardly from the lower portion of the upper section 19 of the door. Guide rollers 25 for said upper door sections are, therefore, carried by hinged plates 26 mounted on the upper section 19, with said guide rollers being engaged in and adapted to follow the curved and horizontal sections of the track 21. The arrangement of the roller carrying plates is such that the projection of the rollers relative to the plane of the door section 19 is variable to compensate for differences in proximity of the face of the door section to the track in different positions on the door. Below the upper section 19 all of the hinges 20 disposed on the side margins of the door sections have journaled therein shafts 27 carrying guide rollers 28 which ride in the tracks 21.

The hinged plates 26 are in the nature of cantilevers and each has its under, angularly directed leaf portion 26' pivotally secured to the upper end portion of an adjustable link, designated generally by the numeral 29 and shown in detail in Figs. 9 and 10. The lower end portion of an adjustable link 29 is pivotally secured to the offset shank portion 30 which has a thin angular keeper blade 31 which straddles the shaft carrying the guide roller 28 projecting from the hinge between the upper two door sections 18 and 19. Each keeper blade projects into the slot between the vertical side margin of the door and the adjacent track 22 and is adapted, when the door is in its closed position, to engage a fixed protuberance 32. The purpose of this arrangement is to urge the upper door section 19 toward its closed position when the entire multi-section door is in its vertical closed position. This is due to the fact that the keeper blade 31, being engaged by the protuberance 32, exerts an upwardly directed force on the adjustable link 29 so that the roller-carrying cantilever plate 26 is urged in a clockwise direction relative to Fig. 2, exerting a closing force on the hinged door section 19. From Fig. 2 it will be noted that when the door, including the upper section 19, is in its closed condition, the guide roller 25 is in the upper extent of the curved section 23 of the track. This tends toward preventing the upper door section 19 from undesirably breaking or folding inwardly. Upon initiation of upward movement of the entire door, then the upper guide roller 25 will ride into the horizontal track section 24 which will permit the upper door section 19 to freely fold

or break inwardly as shown in broken lines in Fig. 2.

The foregoing explanation is made in order that it may be appreciated that the improved latching mechanism, with which the invention is primarily concerned, simultaneously and jointly operates to latch the entire composite door against unauthorized vertical movement and to latch the upper section 19 of the door against any undesirable tendency toward breaking or folding inwardly prior to initiation of vertical movement of the entire door.

Mounted through one of the intermediate sections of the composite door 15 and at a convenient elevation from the ground is a lock barrel 33 in which, as is customary, tumblers are adapted to be actuated by a key inserted into the barrel from exteriorly of the door. Turning the key and the tumblers controlled thereby is effective to turn a lock projection or lug 34 which lodges within a recess 35 therefor in a vertical locking bar 36. Hence, turning movement of the lug 34 in the proper direction, through the engagement of said lug and bar, lifts the bar. The bar is slidably mounted in a bracket 37 on the inner face of the door. As will appear hereinafter, and as is shown in Figs. 7 and 8, when the bar 36 is in its lowered position the latching mechanism, to be described, is released, and when the bar 36 is in its lifted position, the latching mechanism is held or locked in its engaged condition.

The latch mechanism comprises a bell crank lever 38 of bifurcated formation and pivotally mounted as at 39 on the inner face of the door immediately over the vertical locking bar 36. The bell crank lever is adapted to be rocked in a vertical direction by a horizontally disposed plunger bar 40. Said bar is slidably mounted through the door section so as to project outwardly of both faces thereof. Plates on the opposite faces of the door section have inturned stamped flanges 41 which enter the bore in the door section through which the plunger is passed and form bearings for the bar plunger to relieve wear on the stock of the door section. The inner end of the plunger bar is embraced by the lower arms of the bell crank lever 38 and has projecting transverse pin portions 42 engaged within slots 43 in said bell crank lever. The free ends of the other arms of the bell crank lever have pivotally attached thereto the lower ends of a pair of upwardly directed, elongated links 44. From Fig. 1 it will be observed that the intermediate hinge 20 between the door sections 18 and 19 has pivotally mounted on the hinge pintle a pair of toggle links 45. The outer ends of these toggle links embrace the upper ends of the elongated links 44 as well as the lower end of an upper rod 46, all of the same being mounted on a common pivot pin 45'. The upper end of the rod 46 has attached thereto a yoke 47, the side arms of said yoke being slotted as at 48 and the top bar of the yoke having a rectangular slot 49 therein. The flattened depending shank portion 50 of a latching hook 51 extends slidably through the slot 49 in the yoke 47. The depending portion of the hook shank 50 carries a retaining washer 52 which serves to hold on said hook shank 50 a guide disk 53 having laterally projecting pins 54 which ride in the vertical slots 48 in the sides of the yoke 47. It will be observed that the hook shank above the flattened portion 50 is of twisted or corkscrew formation with the result that when there is a relative vertical movement as between the yoke 47 and the hook shank, the hook shank

will be turned or swung in one direction or the other. The yoke 47 is normally maintained in a lowered position relative to the hook shank by means of a confined coiled spring 55. The upper end portion of the latching hook 51 is formed with a horizontal arm at right angles to the shank, said arm terminating in a hook portion 56 which is disposed adjacent the upper edge of the top section 19 of the door.

The frame of the structure surrounding the door opening has on its upper horizontal margin a transverse beam 57 which is adapted to be abutted by the upper marginal portion of the top section of the door when the door is in closed position. The upper face of said beam, intermediate the ends thereof, has anchored thereto an angle plate 58 whose vertical flange 58' is formed with a slot 59 which is adapted to be entered by the hook extremity of the latching hook when the latching hook is swung through an arc from the full line position of Fig. 5 to the broken line position in said view. When this is accomplished, not only is the entire composite door latched against vertical movement but the upper door section 19 is likewise latched against undesired inward swinging or folding, prior to initiation of opening movement of the entire door. The latching hook, which accomplishes both functions, is operated through a single operation transmitted by the rod 48, the toggle links 45, the elongated links 44 and the bell crank lever 38, all previously described. Upward movement of this train of connected elements is accomplished when the locking bar 40 is pushed inwardly from the position of Fig. 7 to the position of Fig. 8. This causes an upward rocking of the bell crank lever and through the means described the latching hook is swung to the latching position shown in broken lines in Fig. 5. The control and operation of the latching mechanism is accomplished from exteriorly of the building through the simple expedient of pushing the bar 40. If it is desired to manipulate the latching mechanism from interiorly of the building this can be readily accomplished by manually swinging the bell crank lever 38.

Operation of the latching mechanism can only be accomplished when the vertical locking bar 36, previously referred to, is in its lowered position. When the latching mechanism is engaged and the locking bar 36 is in its upwardly reciprocated position, the upper free end of said bar 36 engages in a slot 60 in the latching bar 40, thereby holding the latching bar in its innermost position. When the locking bar 36 is reciprocated downwardly, the slot 60 is disengaged, thereby freeing the parts for movement, and downward movement of the yoke 47 and associated connections to accomplish an unlatching movement of the hook 51 is urged by the spring 55.

As was mentioned, the reciprocations of the locking bar 36 are accomplished from exteriorly of the door by the key operated tumblers in the barrel 33, and from interiorly of the building the locking bar may be dropped and released by manually engaging the flanged lower extremity thereof.

The lost motion connection between the yoke 47 and the shank 50 of the latching hook is of considerable importance. It will be appreciated that the train of connected operating members between the bell crank lever 38 and the latching hook 51 traverses the line of hinged connection between the door sections 18 and 19. These sections, in moving from closed vertical position to

overhead position, ride along the curved sections 23 of the tracks 21. If no special provision were made for a yielding shortening in the connections between the members 38 and 51 during movement through the arc of the curved sections of the tracks, an undesirable bending or breaking of said connections would result. This possibility, however, is effectively taken care of by the lost motion connection between the yoke 47 and the shank 50 of the hook 51. When the door sections 18 and 19 are being moved through the arc caused by the curved sections of the track and fold relative to each other, a yielding shortening of the previously mentioned connections is permitted because the yoke then rides upwardly on the hook shank 50, against the tension of the spring 55, permitting the connections to temporarily shorten to an extent to protect them against strain imposed by the folding movement of said door sections. When the door sections reach the overhead position or reach the closed vertical position, the yoke 47 and hook shank 50 float or elongate relative to each other in a rectilinear path to compensatingly increase the over-all length of said connections.

From the foregoing description it will be seen that the improved overhead door mechanism provides efficient and easily operated mechanism for latching the door, including the upper section thereof, and for locking the latching mechanism. These devices have a minimum of projecting parts and do not affect the overhead room required by the door. The door and its associated mechanism are, furthermore, of simple and novel construction and are well adapted for the purposes described.

What is claimed as the invention is:

1. Fastening means for an overhead door of the type which includes a plurality of sections hinged together in superimposed relation to fit in a door frame with tracks adjacent the sides of the door frame curving upwardly therefrom and bearings on the door sections engaging the tracks to guide the door sections into and out of the frame, comprising a latch on the uppermost foldable door section to jointly latch said section against independent swinging movement and the entire door against sliding movement on the tracks, manual control means for the latch mounted on a door section remote from the latch, and a jointed linkage connecting said control means to the latch.

2. Fastening means for an overhead door of the type which includes a plurality of sections hinged together in superimposed relation to fit in a door frame with tracks adjacent the sides of the door frame curving upwardly therefrom and bearings on the door sections engaging the tracks to guide the door sections into and out of the frame, comprising a latch on the uppermost door section to latch it against swinging movement and to latch the entire door against sliding movement on the tracks, manual control means for the latch, and a jointed linkage connecting said control means to the latch, said linkage including therein a yielding lost motion connection to permit automatic shortening and elongation of said linkage.

3. Fastening means for an overhead door of the type which includes a plurality of sections hinged together in superimposed relation to fit in a door frame with tracks adjacent the sides of the door frame curving upwardly therefrom and bearings on the door sections engaging the tracks to guide the door sections into and out of the frame, comprising a swingable latch hook movably mounted

on the uppermost door section, a fixed female latch plate carried by the door frame to engage said hook, an elongated, jointed linkage connected at one end with said hook and reciprocable to swing said hook, and manual control means projecting from a door section remote from the hook and engaging the linkage to reciprocate the latter.

4. Fastening means for an overhead door of the type which includes a plurality of sections hinged together in superimposed relation to fit in a door frame with tracks adjacent the sides of the door frame curving upwardly therefrom and bearings

on the door sections engaging the tracks to guide the door sections into and out of the frame, comprising a swingable latch hook mounted on the uppermost section of the door, a fixed female latch plate carried by the door frame to engage said hook, an elongated, jointed linkage reciprocably mounted on the door, a yielding, lost motion connection between the linkage and the hook, said connection including means effective to swing the hook, and a reciprocatable plunger mounted through the door remote from the latch hook and engaging the linkage to reciprocate it.

CHRIST BUEHNER.
